UNITED STATES PATENT OFFICE.

EVARISTE E. TALBOT, OF FALL RIVER, MASSACHUSETTS.

ADJUSTABLE CAM.

Application filed December 11, 1922. Serial No. 606,106.

To all whom it may concern:

Be it known that I, EVARISTE E. TALBOT, a citizen of the United States, residing at Fall River, in the county of Bristol and 5 State of Massachusetts, have invented certain new and useful Improvements in Adjustable Cams, of which the following is a specification, reference being had therein to the accompanying drawings.

10 My invention relates to adjustable cams, and, more especially, to such as are embodied in a loom for operating the picker-stick thereof, and as are removably connected to the cam-shaft.

15 The primary object of my invention is to provide a cam that may be adjusted in numerous positions in relation to the cam-shaft; and that may be removably secured to the cam-shaft; while the second object is to provide a cam, of the above-mentioned capabilities, that has two or more cam-surfaces delivering two or more blows for each revolution of the cam-shaft; and, when in operative position, has the weights of its various 20 parts arranged so as to form a balanced rotatable body, thereby reducing the reaction of the cam-shaft on the cam-shaft gear and crank-shaft gear, hence diminishing the vibrations of the loom, the loosening of its 25 parts, and the breakage of the teeth of the gears, due to the blows struck by the cam-point while operating the picker-stick.

Other objects of my invention will appear hereinafter.

30 In the drawings illustrating the principle of my invention and the best mode now known to me of embodying the same in operative structure,

Fig. 1 is a rear elevation of my invention; 35 Fig. 2 is a vertical section on line 2—2

Fig. 1;

Fig. 3 shows my invention in front elevation;

Fig. 4 is a front elevation of my invention, one of the cam-point members being moved out of engagement with, and away from, the hub-plate and the cam-plate members; while

Fig. 5 is a like view of two cam-point members, and one cam-plate member of the cam-plate, being moved out of engagement with, and away from the hub-plate;

Fig. 6 is a like view of the hub plate;

Fig. 7 shows in rear elevation, the two cam-plate members of the cam-plate;

Fig. 8 shows a rear elevation of the modified form of my invention, where there is only one cam-point member.

A hub-plate 1, in the form of a disc, is fixed, as by set-screws 2, to a cam-shaft 3, 60 suitably mounted in bearings in a loom, not shown. On its operating face is a series of raised radial locking corrugations 4, designed to interlock with similar corrugations 5 upon a cam-plate 6. This plate consists of two cam-plate members 7, 8, and two cam-point members 9, 10, all of which, when secured together, form a pick and pick cam, such, for example, as is required on pick and pick box-looms. Each cam-plate 70 member is somewhat segmental in form, and, when in operative position, in relation to the hub-plate, the chord 11 of segment 8 is parallel with chord 12 of segment 7, and is adjacent to the hub 13 of the hub-plate 1. 75 Each cam-point member, as 9 and 10, has two parallel sides, as 14, 15, and 16, 17 respectively, that fit those of the opening formed between the cam-plate members 7, 8; and also a semi-circular bore as 18 and 19, to fit the side of the hub 13 of the hub-plate 1. These chords and sides are preferably parallel, to obviate the tendency of the cam-point member to work loose, were they at an acute angle.

85 The hub-plate has four adjusting slots, 20, 21, 22 and 23, and, as here shown, each may be separated from that next adjacent, as by 90 degrees. Corresponding to these are four bolt holes 24, 25, 26, and 27, one in each 90 of the two cam-plate members, and of the two cam-point members, for the reception of suitable bolts, with washers and nuts, when the members are in operative position in relation to the hub-plate; also there are 95 corresponding bolt holes 28, 29, 30 and 31, in the cam-point members 9, 10, and cam-plate members 7, 8, and bolts to pass through these holes, and be there secured by washers and nuts; the radial corrugations 4, 5, of the 100 adjacent faces of the hub-plate 1 and the entire cam-plate 6, adjustably interlocking, and all of the parts becoming rigidly bound together.

105 The method of using this embodiment of my invention has already become obvious, probably. Should it be necessary to remove either one or both of the cam-point members, see Figs. 4 and 5, then all that is required, is a removal of the two bolts passing through 110

one or both of said members; and a longitudinal movement of said member or members; this disengages the interlocking corrugations, and each cam-point member may 5 thus be freed. It is to be noted that the cam-plate members 7 and 8, Fig. 4, remain locked to the hub, so that when the cam-point member, new or old, is replaced in its respective slot, the timing of the operation of the cam remains as originally determined.

Should it be essential that one or both of the cam-plate members be removed, then, in addition to the removal of the cam-plate 15 just described, the bolts securing the cam-plate members 7 and 8, Fig. 5, to the hub-plate 1, are taken out, the cam-plate members first moved longitudinally of the hub-plate, enough to disengage the locking corrugations, and then moved away from the cam-shaft 13, Fig. 5.

To replace the cam-plate members and/or the cam-point members, a reversal of the above-described operation is to be pursued.

Attention is called to the following facts:—That notwithstanding the hub-plate is secured to the shaft by set screws, the cam-plate 6 may, within certain limits, be advanced or retarded in relation to the hub-plate, by reason of the bolts and adjusting slots 20, 21, 22 and 23, Figs. 4, 5 and 6, in the hub-plate 1; that the cam-plate can be removably secured to the hub-plate, in any one of four positions, say 90 degrees apart; that the slots in the hub-plate are elongated circumferentially, and permit a general adjustment, forward and back, at any one of said four positions, 90 degrees apart.

It is also to be noted that because each cam-plate-member and its cam-point-member are like the other cam-plate member and cam-point in form and weight, the cam-plate becomes a balanced rotatable body, and the cam-shaft turns evenly in its bearings.

Should the entire cam-plate have to be removed from the hub-plate, it can be so removed, and also replaced, without interfering with the timing of the other moving parts of the loom, provided that before the removal, suitable marks are made on the cam-plate and hub-plate to indicate their proper co-operating positions.

To change or replace my pick-cam-plate requires not more than twenty minutes. If 55 only a cam-point member has to be removed, returned or replaced, plainly a much shorter time is needed.

It is to be noted that no machine work is required on the cam-point member or the cam-plate members, for they are castings, the only machine work being boring and reaming the hub-plate, which practically never has to be removed from the shaft.

In short, my invention is durable, cheap 65 in cost, quickly changed or replaced in the

loom, and reduces greatly the losses arising from the use of pick cams heretofore used.

In Fig. 8 is shown what, at first glance, would seem to be identical with the invention described and claimed in a pending application for U. S. Letters Patent No. 523,830, filed by me December 21, 1921; but it is not identical, for the reason that it may be adjusted forward or back in any one of numerous different positions, say 90 degrees apart, in relation to the cam-shaft or hub-plate, while the cam mentioned in said application is adjustable forward and back, only in one position.

Desiring to protect my invention in the broadest manner legally possible, what I claim is:

1. A pick-cam having a hub-plate fixed to the shaft of a loom; a cam-plate; a parallel-sided opening extending from the hub of the hub-plate so as to form an opening with parallel sides, to the end of the cam-surface, to permit the removal or the replacement of the cam-plate without disturbing the operative position of the cam-shaft; a cam-point member having parallel sides permitting said member to be moved into operative position in said opening in the cam-plate; means for securing the cam-plate and cam-point member to the hub-plate in any one of three or more different positions; and means whereby the said cam-plate and cam-point member may, in any one of said three or more of said positions, be adjusted forward or back, in relation to the hub-plate.

2. A pick-cam having a hub-plate fixed to the cam-shaft of a loom, and having locking corrugations upon its operative face; a cam-plate having a parallel-sided opening; a cam-point member having parallel sides permitting said member to be moved into operative position in said side opening of the cam-plate; locking corrugations upon the cam-plate and the cam-point member to engage the corresponding locking corrugations upon the face of the hub-plate; and means for securing in locking engagement, the cam-plate and the cam-point member to the hub-plate in any one of various circumferential relations to the hub-plate.

3. A pick-cam comprising a hub-plate; and a double cam-plate made up of a pair of cam-plate members and a pair of cam-point members, each with a portion of the entire double cam surface; means for removably securing the cam-plate members to the hub-plate so as to form an opening with parallel sides extending from the hub of the hub-plate to the opposite ends of the cam surface; each of the cam-point members having sides to engage the sides of the said opening, and having its cam-surface continue that of one cam-plate; and means to secure each cam-point member to the hub-plate; all designed to form a balanced rotatable body,

and to permit said members to be removed, or replaced, without disturbing the operative position of the cam-shaft.

4. A pick-cam having a hub-plate fixed 5 to the cam-shaft of a loom, and having locking corrugations upon its operative face; a cam-plate having a parallel-sided opening; a cam-point member having parallel sides permitting said member to be moved 10 into operative position in said side opening of the cam-plate; locking corrugations upon the cam-plate and the cam-point member to engage the corresponding locking corrugations upon the face of the hub-plate; and 15 means for securing in locking engagement, the cam-plate and the cam-point member to the hub-plate in any one of four positions in circumferential relations to the hub-plate.

5. A pick-cam comprising a hub-plate; 20 and a double cam-plate made up of a pair of cam-plate members and a pair of cam-point members, each with a portion of the entire double cam-surface; means for removably securing the cam-plate members in 25 different positions in circumferential relations, to the hub-plate, and so as to form an opening with parallel sides extending from the hub of the hub-plate to the opposite ends of the cam-surface; each of the cam-point 30 members having sides to engage the sides of the said opening, and having its cam-sur-

face continue that of one cam-plate; and means to secure each cam-point member to the hub-plate; all designed to form a balanced rotatable body, and to permit said 35 members to be removed or replaced without disturbing the operative position of the cam-shaft.

6. A pick-cam for a loom, comprising a hub-plate; and a double cam-plate made up 40 of a pair of cam-plate members and a pair of cam-point members, each with a portion of the entire double cam-surface; means for removably securing the cam-plate members in any one of four positions in circumferential 45 relations to the hub-plate and so as to form an opening with parallel sides extending from the hub of the hub-plate to the opposite ends of the cam-surface; each of the cam-point members having sides to engage the sides of the said opening and having its cam-surface continue that of one cam-plate; and means to secure each cam-point member to the hub-plate; all designed 50 to form a balanced rotatable body and permit said members to be removed or replaced without disturbing the operative positions of other parts of the loom.

In testimony whereof I hereunto affix my signature.

EVARISTE E. TALBOT.
